UNITED STATES PATENT OFFICE.

WILLIAM W. DOTY, OF GREAT KILLS, NEW YORK.

CAR-DOOR-MOVING MECHANISM.

Application filed December 15, 1921, Serial No. 522,533. Renewed September 27, 1928.

The invention relates to doors of compartments, more particularly to doors of the sliding type employed, for example, in the case of freight cars.

5 It has for its object to associate with said doors means whereby they may be readily moved, in opening and closing same, and without causing damage to the side of a car or the like, as frequently occurs in the present 10 practice. A further object of the invention consists in associating with such means for moving the door, means whereby the latter may also be sealed and cleated without the usual devices employed for this purpose, 15 either in fully closed or partly opened position, to prevent burglarizing and unauthorized entry.

To this end, the invention consists in providing on the side of the car or the like and 20 in combination with an abutment member, best set in the outer face of the side of the car, a novel lever member which is carried by the door and which may serve also as a means for securely sealing said door to the side as well 25 as operating as a cleat. A further object of the invention consists in novel means for mounting the lever and for sealing same.

The nature of the invention, however, will best be understood when described in connection 30 with the accompanying drawings, in which—

Fig. 1 is a perspective view of a portion of a freight car, showing one embodiment of the invention, with sliding door thereof and 35 the associated moving and sealing means.

Figs. 2 and 3 are fragmentary, transverse sectional views illustrating different positions of the lever in the operation of moving the sliding door.

40 Fig. 4 is a perspective view of the sealing means.

Fig. 5 is a transverse section taken on the line 5—5, Fig. 4, looking in the direction of the arrows.

45 Similar characters of reference designate corresponding parts thruout the several views.

Referring to the drawings, 10 designates a compartment, for example, the body of a freight car having a side 11 with door open-

ing and over which is slidably mounted in any suitable manner a door 12, limited in its closed and fully opened positions as by cleats 13, all of which is well understood and form no particular part of the present invention. 55

In accordance with the present invention, there is set in or otherwise suitably secured to the side 11 an abutment member in the nature of a rack 15, having bounding walls 16 which may also project slightly beyond the face of the side 11 to afford a track for guiding the door. The rack is located conveniently for operation, for example, slightly above the middle of the car side 11 and extends over 60 substantially the width of the door 12. 65

There is mounted on the door 12 a block 20 which affords bearings 21 and 22 for a sliding bolt 23; and the bearing 22, is further provided with an outwardly extending lug 24 having a slot 25 therein. There is, moreover, fixedly secured to the bolt 23, between the two bearings 21 and 22, a lug 26 having a slot 27 designed to register with the slot 25 when the bolt is slid outwardly and the lug 26 turned over. The latter serves also to 70 hold the bolt to the block. In the retracted position of the bolt, the lug 26 is maintained in position against the face of the plate by means of a rib 28 extending from the bearing 21 and upon which an edge of the lug 26 bears 75 to throw the lug back. 80

There is further arranged to be held by the block 20 an actuating lever 30 having a slot 31 with recess 32 and thru which there is adapted to pass a stud 33 fitting into a boss 85 34 of the block, whereby the lever is pivotally attached to the said block and in manner such that the said lever may have a limited lateral play, for the purpose hereinafter set forth, in addition to its rocking motion about the stud 33. At its upper end, the lever is provided with two noses 35 and 36 which are so positioned as to be suitable for individual engagement with the teeth of the rack 15, when the lever 30 is in the position either as 90 shown in Fig. 2 which is for operation vertically as when there are no obstructions, or for the position shown in Fig. 3 for operation substantially horizontal, as when a platform or the like 37 necessitates the elevation of the 100

lever, as shown. The mounting of the lever in the slot 31 is such as to admit of rocking either of the noses in the manner aforesaid; and, in either position, by rocking said lever laterally with the nose 35 or 36 between successive teeth, the door 12 may gradually be pulled or pushed to open or close same. In this manner, sufficient power will be available to move the door laterally and no disfigurement or damage of the car side 11 results, as is the case in the methods usually employed when the door presents considerable resistance.

The lever 30, moreover, may be employed as a means for sealing and cleating the door 12 either in partly opened position as for ventilation, or in fully closed position, thereby preventing burglarizing of the contents and unauthorized entry. To this end, there is provided in the upper portion of the lever an eye 40 having a notch 41; and the bolt, when slid outwardly, is arranged to pass thru said eye together with a projection 42 thereon which is accommodated by the notch 41. By turning the bolt over thru the lug 26, which for this purpose is provided with a finger-piece 43, projection 42 will hold the bolt against movement and the lever against vibration; and the two lugs 24 and 26, having their slots 25 and 27 registering, a suitable sealing wire or the like 44 may be brought therethru to seal the door. The car cannot then be opened until the seal is removed and lug 26 is turned over, when the projection 42 of the bolt will register with notch 41 of the lever and allow the bolt to be retracted. The lever 30, moreover, may, when the car is not sealed, be retained in vertical position with its nose 36 in the rack by hanging it on stud 33 in the recess 32 of its slot 31; and it is also then in the proper position for actuating the lever vertically.

I claim:—

1. In a door operator, the combination with a wall having a door opening, a door mounted over same, a rack set in the wall with its teeth at right angles thereto, and a pivoted normally vertically depending and bodily movable lever carried by the door, having a nose movable toward the door to a position to directly engage between two of the teeth of said rack and laterally the said lever being also oscillable to move the door when thus engaged.
2. In a door operator, the combination with a wall having a door opening, a door mounted over same, a rack set in the wall, and a lever carried by the door and adapted to directly engage the teeth of said rack, said lever being slotted to permit of its assuming two different positions for engaging the teeth of said rack.
3. In a door operator, the combination with a wall having a door opening, a door mounted over same, a rack set in the wall, and a lever

carried by the door, said lever being slotted to permit of its assuming a substantially vertical and horizontal position for engaging the teeth of said rack.

4. In a door operator, the combination with a wall having a door opening, a door mounted over same, a rack set in the wall, and a lever carried by the door, having two noses and slotted to allow it to assume two different positions, whereby either of the two of said noses may engage the teeth of said rack.

5. In a door operator, the combination with a wall having a door opening, a door mounted over same, a rack set in the wall, a lever carried by the door and adapted to directly engage the teeth of said rack, said lever being provided with an eye, a block secured to the door and having bearings, a bolt slidable in said bearings, one end thereof being designed to pass thru the eye of the lever, and means for sealing said bolt to the block.

6. In a door operator, the combination with a wall having a door opening, a door mounted over same, a rack set in the wall, a block secured to the door, a bolt slidable thereon, a lever pivotally secured to said block and provided with an eye for the bolt, having a limited lateral play and adapted to directly engage the teeth of said rack, a slotted lug extending from said block, a slotted lug carried by the bolt, the slots of said lugs being adapted to register in one position of the bolt, and means to secure the slotted lugs to each other.

7. In a door operator, the combination with a wall having a door opening, a door mounted over same, a rack set in the wall, a block secured to the door, a bolt slidable thereon, a lever pivotally secured to said block and provided with an eye for the bolt, having a limited lateral play and adapted to directly engage the teeth of said rack, a slotted lug extending from said block, a slotted lug carried by the bolt, the slots of said lugs being adapted to register in one position of the bolt, and means to secure the slotted lugs to each other, the block being provided with means to normally maintain the lug of the bolt in position such that its slot does not register with the slot of the block lug.

8. In a door operator, the combination with a wall having a door opening, a door mounted over same, a rack set in the wall, a block secured to the door, a bolt slidable thereon, and provided at its outer end with a projection, a lever pivotally secured to said block and provided with a notched eye to permit the outer end of the bolt to pass therethru, having a limited lateral play and adapted to directly engage the teeth of said rack, a slotted lug extending from said block, a slotted lug carried by the bolt, the slots of said lugs being adapted to register in one position of the bolt, and means to secure the slotted lugs to each other.

9. In a door operator, the combination with a wall having a door opening, a door mounted over same, a rack set in the wall, a slotted lever carried by the door and adapted to directly engage the teeth of the rack, the slot of said lever being provided with a recess, and a stud for pivotally attaching the lever

to the door and when in the said recess retaining the lever in a vertical position.

Signed at New York, in the county of New ¹⁰ York and State of New York this 12th day of December A. D. 1921.

WILLIAM W. DOTY.
